UNITED STATES PATENT OFFICE.

WARREN FUHRMANN, OF WESTFIELD, NEW JERSEY, AND EDWARD M. SQUAREY, OF TUCKAHOE, NEW YORK, ASSIGNEES, BY MESNE ASSIGNMENTS, TO WILKINSON BROTHERS AND COMPANY, INCORPORATED, OF NEW YORK, N. Y., A CORPORATION OF NEW YORK.

LOCK FOR CALCULATOR TYPE-CARRIERS.

1,292,301.

Specification of Letters Patent. Patented Jan. 21, 1919.

Application filed April 23, 1917. Serial No. 164,007.

To all whom it may concern:

Be it known that we, WARREN FUHRMANN, a citizen of the United States, and a resident of Westfield, in the county of Union and State of New Jersey, and EDWARD M. SQUAREY, a subject of the King of Great Britain, and a resident of Tuckahoe, county of Westchester, and State of New York, have invented certain new and useful Improvements in Locks for Calculator Type-Carriers, of which the following is a specification.

This invention has for its object to provide means for accurately positioning the rack and type carriers or plates in calculating machines in the several positions to which advanced after the selection of the type plates by the several keys; which mechanism will cause the locking member to engage the rack bars during the latter portion of its advance stroke, and which will further serve to retain the lock bars in locking position for the remainder of the advance movement.

A further object of the invention is to provide in connection with such mechanism, a special form of offset teeth and coöperating portion of the lock bar, whereby to facilitate the proper engagement and positioning of the rack and type plates.

In the accompanying drawings showing one embodiment of our invention, Figure 1 is a plan view of the device applied to a calculating machine. Fig. 2 is a side elevation of the parts in the normal position. Fig. 3 shows the same parts in the advanced positions. Fig. 4 shows one of the cam plates separately; and Fig. 5 shows one of the levers and the locking bar in section.

In the construction of machines of this character it is customary to have a set of stop bars that are advanced on depression of an item key; and also rack and type plates that are permitted to advance when the handle or main shaft is actuated. The rack and type plate will move until it engages the advanced stop bar whereby the type corresponding to the stop bar and key advanced will be positioned opposite the platen for printing by engagement with the hammer. But as the type bars are usually advanced by spring pressure as permitted by the rising of the universal bar, when the

stop on the type bar strikes the advanced stop bar there will be more or less vibration tending to bring the type bar out of its exact correct position for printing, which is done at once, by the hammer. The purpose of the present invention is to cause a lock bar to engage all of the advanced type bars, in whatever position that they may have been brought, before the hammer strikes the positioned type on the type bar. Obviously, with such a construction the type bar cannot advance too far or beyond the correct position because of its engagement with the stop bar, but it will somewhat rebound and may assume a position slightly below the correct one for printing. Therefore, we provide a series of offset teeth or an extension of each type plate or carrier, and a lock bar to coöperate therewith, that are constructed with beveled ends or engaging edges that will move the type bar upwardly if depressed below its proper position for printing.

As shown in the drawing there are a series of rack and type plates 6 that are moved upwardly along guide post 7 by springs 8; and the type plates have lugs 9 projecting rearwardly that engage a universal bar 10. The latter is mounted on a pair of arms 11 on a main shaft 12 that is rocked by an arm 13 on a pitman 14, that is reciprocated by the handle or actuating shaft. These parts are shown in their normal position in Fig. 2, and with the universal bar fully elevated in Fig. 3. On the front of each rack and type plate 6 is a lug 15 that will engage any one of a set of stop bars 16 that are advanced by depression of a key 17, see Fig. 1. When the universal bar is swung upward the rack and type plate 6 will be moved upwardly by the spring 8 until the lug 15 engages one of the stop bars 16 that may have been advanced by depression of a key, as shown in Fig. 3. The rack and type plate will thus be arrested, while the universal bar continues its upward movement. The type 18 on the rack and type plate corresponds in position with the stop bars 16, and hence one of these will be positioned opposite the platen 19, when the stop arrests the rack and type plate, as shown in Fig. 3. The spring 8 would tend to hold the rack and type plate with the lug engaging the

stop bar 16; but as this movement is generally very rapid, the rack and type plate would tend to rebound and move downwardly that would bring the type 18^x below the proper printing position.

To overcome this objection we provide a series of teeth 20 on an extension 21 of the type plate or carrier 6, which teeth are offset to permit entrance of a lock bar 22 therebetween. These teeth also have their extremities 23 beveled as shown, and the lock bar 22 is carried by a pair of arms 25, pivoted at 28 on the side plates 26 and 27 of the printing section 37 of the machine, see Fig. 1. These arms 25 are swung by springs 29 to move the lock bar away from the teeth 20. On the plates 26 and 27 are also pivoted cam plates 30. Each cam plate has a concentric rear edge 31 and a recessed portion at 32 connecting with the concentric portion 31 by an eccentric portion or cam 33. Each lever 25 has a stud 34 that is normally held in the recess 32 by the action of the springs 29. A spring 35 is connected with each cam plate 30 to hold it in the position shown in Fig. 2, with the stud 34 engaging the extension 36 of the cam plate.

The parts being in the normal position of Fig. 1, and the universal bar being raised after the stop bar 16 has been advanced, the swinging of the shaft 12 will first permit the universal bar 10 to elevate, bringing the rack and type plate to engage the stop bar, whereupon the further rising of the universal bar 10, after it has caused the lug 15 to pass beyond the range of all of the stop bars 12, will bring the universal bar to engage the two cam plates 30 at their front ends. These plates will thus be swung to lower their rear portions engaging the studs 34. The cam plate will very shortly bring the cam portion 33 to engage the studs on the arms 25, that will rock the arms and move the lock bar 22 rearward. This lock bar and the rack and type plates are so relatively positioned, that when the lug 15 is engaged with a stop bar 16, the lock bar will be swung between two adjacent teeth 20 on the type plate extension. This will serve the lock or accurately position the rack and type plate in the proper position for printing. The further advance of the universal bar and swinging of the cam plates will bring the concentric portion 31 to engage the studs 34, and the arms 25 and lock bar will be retained in the locking position, for the remainder of the movement of the universal bar.

But, if the rack and type plate should rebound and take a position slightly below that indicated in Fig. 3, then the beveled edge of the lock bar 24 will strike the beveled edge 23 of the tooth just above the recess into which the lock bar should enter. The tooth and the rack bar having inclined faces, will coöperate to force the rack and type plate

upwardly the proper distance until the lock will enter the space or recess between the teeth. It will be observed that from this construction of the teeth and the lock bar, the rack and type plate could rebound a considerable distance, as long as the two inclined faces of the lock bar and of the tooth above the proper recess, are brought together. It will be understood that as soon as the universal bar begins to descend, the springs 35 will retract the cam plates, and very shortly the studs will pass beyond the concentric edges and be engaged by the recess in the cam plates, whereupon the springs 29 will swing the arms and withdraw the lock bar at once from the rack and type plate recess between the teeth; which will return these parts to normal position.

Having thus described our invention, what we claim is:—

1. In a calculating machine, a rack and type plate provided with a carrier portion, type in the carrier portion, the plate having a set of teeth corresponding in relative position to the type on the carrier portion, a pair of levers pivoted on the machine, a lock bar carried by said levers to be shifted thereby to and from said teeth, a stud carried by each of said levers, a cam plate pivoted for engagement with each of said studs respectively, a universal bar arranged to control the movement of a rack and type plates, said plates being in position to be swung by the universal bar at the latter portion of its advance movement, said cam plates being shaped to first swing said levers to shift the lock bar into engagement with said teeth, and to retain the levers and lock bar in such position for the remainder of the advance of the universal bar, and means for holding said levers to press the studs against the cam plate.

2. In a calculating machine, a rack and type plate provided with a carrier portion, type in the carrier portion, the plate having a set of teeth corresponding in relative position to the type on the carrier portion, a pair of levers pivoted on the machine, a lock bar carried by said levers to be shifted thereby to and from said teeth, a stud carried by each of said levers, a cam plate pivoted for engagement with each of said studs respectively, said plates being in position to be swung by the universal bar at the latter portion of its advance movement, said cam plates being shaped to first swing said levers to shift the lock bar into engagement with said teeth, and to retain the levers and lock bar in such position for the remainder of the advance of the universal bar, and means for holding said levers to press the studs against the cam plate, said teeth on the plate engaged by the lock bar having their extremities all inclined in the same direction and being offset to receive the lock bar

between adjacent teeth, said lock bar having a beveled edge to coöperate with said teeth.

3. In a calculating machine, a rack and type plate provided with a carrier portion, type in the carrier portion, the plate having a set of offset teeth corresponding in relative position to the type on the plate, a pair of levers pivoted on the machine, a lock bar carried by said levers and arranged to engage said teeth and enter the space between the same, a pair of cam plates pivoted on the machine, a stud on each of said levers, springs on said levers 10 to press the studs against the cam plates and retract the lock bar from the teeth, said cam plates being engaged by the universal bar at the latter portion of its advance, and a spring for retracting the cam plates on 15 return of the universal bar, said cam plates being arranged to engage said studs by an eccentric portion to first shift the levers and cause the lock bar to enter between said teeth, said cam plate on further advance of 20 the universal bar engaging the studs by a concentric portion for the remainder of the advance stroke to hold the lock bar in engagement with said teeth.

4. In a calculating machine, a rack and type plate provided with a carrier portion, type in the carrier portion, the plate having a set of offset teeth corresponding in relative position to the type on the plate, a pair of levers pivoted on the machine, a lock bar 30 carried by said levers and arranged to engage said teeth and enter the space between the same, a pair of cam plates pivoted on the machine, a stud on each of said levers, springs on said levers to press the studs 35 against the cam plates and retract the lock bar from the teeth, said cam plates being engaged by the universal bar at the latter portion of its advance, and a spring for retracing the cam plates on return of the 40

universal bar, said cam plates being arranged to engage said studs by an eccentric portion to first shift the levers and cause the lock bar to enter between said teeth, and said cam plate on further advance of the universal bar engaging the studs by a concentric portion for the remainder of the 45 advance stroke to hold the lock bar in engagement with said teeth, said teeth on the plate engaged by the lock bar having their extremities all inclined in a general direction and being offset to receive the lock bar between adjacent teeth, said lock bar having a beveled edge to coöperate with said teeth.

5. In a calculating machine, a rack and type plate provided with a carrier portion, type in the carrier portion, the plate having a set of teeth corresponding in relative position to the type on the plate, a lock bar movably supported on the machine to engage between the different teeth as the said plate is shifted to different printing positions, a universal bar arranged to control the movement of all the rack and type plates, means for normally holding said lock bar away from the rack and type plate, and means connected with the lock bar arranged to be engaged by the universal bar when advanced to first shift the lock bar to engage the rack and type plate at said notches, and to retain the lock bar in locking position for the remainder of the stroke of the universal bar, said teeth on the plate engaged by the lock bar having their extremities all inclined from side to side in the same direction and being offset to receive the lock bar between adjacent teeth, said lock bar having its edge inclined from side to side in the same direction to coöperate with said teeth.
